UNITED STATES PATENT OFFICE

EDMOND J. McCARTY, OF CHICAGO, ILLINOIS

CAR RERAILER

Application filed October 25, 1929. Serial No. 402,483.

The present invention consists of a car rerailer for replacing a derailed car or engine on the tracks.

It is well-known in the art to equip rails with various means for returning a car to its tracks after it has been derailed and the present invention is designed as an improvement to more effectively secure the rerailer to the track and ties, and for returning the car, with a minimum of resistance, to the rails, without fracturing or damaging the rerailing apparatus or the car.

Further objects of the invention are to provide a rail ball embracing portion on the rerailer to prevent casual displacement of the latter and to equip the rerailer with anti-creeper means to prevent movement of the rerailer while the car is being engaged therewith, the means eliminating the use of spikes or other securing elements which are customarily driven into the ties for anchoring a rerailer.

Still another object of the invention is to provide a rerailer body which extends in parallelism with the rail for an appreciable distance and is positively though detachably engaged with the rail throughout the entire length of the rerailer, the latter being equipped with tie embracing means which will positively and effectively hold the rerailer from longitudinal displacement while the car is being engaged therewith, without causing mutilation or displacement of the tie.

Other objects of the invention will be apparent from the following description of the present preferred form, taken in connection with the accompanying drawings, wherein

Fig. 1 is a top plan view of a rerailer constructed in accordance with the present invention;

Fig. 2 is a side elevational view thereof, looking at the non-rail engaging side thereof;

Fig. 3 is a similar view, looking from the opposite or rail engaging side;

Fig. 4 is an end elevational view of the same, illustrating its application to a rail and tie, the latter being shown fragmentarily;

Fig. 5 is a similar view, looking from the end opposite to that shown in Fig. 4;

Fig. 6 is a sectional view, taken on the line 6—6 of Fig. 1, looking in the direction of the arrows;

Fig. 7 is a transverse sectional view, taken on the line 7—7 of Fig. 1;

Fig. 8 is a transverse sectional view, taken on the line 8—8 of Fig. 1; and

Fig. 9 is a transverse sectional view of a slightly modified form of rerailer.

In order to illustrate the application of this invention I have shown in the drawings rail ties 10 of standard construction, which are equipped with rails 11, also of conventional design. The rerailer constructed in accordance with the present invention embodies a base, generally designated 12, which extends from one end of the rerailer to the other and issues into a web portion 13, the upper terminal of which latter merges into a platform generally designated 14. The platform 14 comprises a wheel traversing channel 15, and a wheel tread portion 16. In actual use, the tread portion would be a couple of feet long, to parallel the rail for an appreciable distance. The channel 15 of the platform extends beyond one end of the tread 16 and is disposed at an inclination, as indicated at 17, this constituting the car engaging end of the rerailer. The inclined portion of the channel is equipped with a supporting leg or flange 18, which parallels the base 12.

The lateral margin of the tread 16 opposite to that which issues into the channel portion 15 of the platform, is equipped with rail embracing lugs or hooks 19, one being formed at each end of the tread to positively retain the platform from lateral displacement. It will be noted, especially upon reference to Fig. 5 of the drawings, that each of the hooks 19 extends downwardly in parallel relation to one side of the ball of the rail and has its bill engaged directly beneath the ball. Consequently, to engage or disengage the rerailer with the rail it is necessary to dispose the rerailer at an angle of approximately forty-five degrees (45°). In this way casual displacement of the rerailer from the rail is posi-

tively eliminated. Moreover, the tread portion 16 of the platform is superimposed on the rail so as to sustain the load incident to the passage of an engine or car thereover and eliminates the possibility of the lugs or hooks 5 coming in contact with the wheels of the car. By making the tread relatively long, the wheel of the car or engine is compelled to travel for an appreciable distance thereover, 10 before being re-engaged with the rail, thereby positively effecting replacement of the car or engine on the rail without possibility of lateral displacement of the rerailer or any portion of the latter until the replacement 15 of the car or engine has been effected to a point of complete safety.

The inclined portion 17 of the platform has a portion extended from its lower face at one end to provide a tie abutment 20 which 20 extends completely across the inclined end 17 to cover a substantial portion of the tie, as illustrated to advantage in Fig. 4. Since the abutment is formed on the car receiving end of the platform, it is apparent that pressure against said receiving end urges the 25 abutment into snug engagement with the tie to prevent longitudinal displacement of the rerailer. This device eliminates the use of spikes or any other securing means, yet the 30 rerailer is effectively held in place without possibility of mutilating or displacing the ties.

It will be noted, especially upon reference 35 to Figs. 5, 7 and 8 of the drawings, that the inner portion of the rail channel which issues into the tread 16 is abruptly raised to provide a flange 21, which is parallel to the hooks 19 and embraces one side of the rail. If desired, however, the channel may be uniplanar with 40 the tread 16, as shown in the form of invention illustrated in Fig. 9, wherein the channel is indicated at 15' and the tread at 16'. When this form of invention is used, a flange 21' is 45 formed on the lower face of the platform at the jointure of the channel and tread, which serves in the same capacity as the flange 21.

In use of this device, it is of course understood that one rerailer is engaged on the inside of one rail and the other rerailer engaged with the outside of the opposite rail, in a manner well-known in the art. Engagement is accomplished with the present invention by disposing the same at an angle of approximately forty-five degrees (45°) to 50 permit the hooks 19 to be slipped over the ball of the rail, after which the rerailer is permitted to gravitate into engagement with the ties. The hooks positively prevent lateral displacement of the rerailer, while longitudinal displacement is prevented by the 55 abutment 20. Each of the rerailers consists of a unit in itself, to increase its strength and longevity, in addition to reducing the cost of manufacture to a minimum.

60 It is of course, to be understood that va-

rious changes may be made in my invention, especially in the details of construction and operation, within the scope of the appended claims.

What is claimed is:

1. A car replacer, including a body engageable with the rail ties in contiguity to the rail and equipped with a lateral extension at each end projecting over the ball of the rail and extending beneath the latter. 70

2. In combination, with car rails and ties, a car rerailer including a body embodying a wheel receiving platform extending in superposed relation to the rail for an appreciable distance, a portion of each end of the platform being laterally extended to provide a rail engaging hook extended beneath the ball of the rail, one end of said platform being inclined downwardly for engagement with a tie. 75

3. A car replacer including a unitary body formed to provide a wheel channel equipped with a base for engaging with rail ties, a tread portion issuing from one of the lateral margins of said wheel channel and equipped with hooks at the opposite ends thereof for engagement with and beneath the ball of a rail, one end of said channel being extended and inclined downwardly to engage a tie, and equipped with an extension forming an abutment to prevent longitudinal displacement of the rerailer. 85
